UNITED STATES PATENT OFFICE.

CHARLES E. BLAIR, OF DORCHESTER, MASSACHUSETTS, ASSIGNOR TO AMERICAN
WARP-DRAWING MACHINE COMPANY, A CORPORATION OF MAINE.

DETACHED HEDDLE OR THE LIKE.

1,153,858.

Specification of Letters Patent. Patented Sept. 14, 1915.

Original application filed May 8, 1909, Serial No. 474,885. Divided and this application filed March 12, 1914. Serial No. 824,250.

To all whom it may concern:

Be it known that I, CHARLES E. BLAIR, a citizen of the United States, and a resident of Dorchester, county of Suffolk, State of Massachusetts, (whose post-office address is 195 Freeport street, Dorchester, Massachusetts,) have invented an Improvement in Detached Heddles or the like, of which the following description, in connection with the accompanying drawings, is a specification, like characters on the drawings representing like parts.

This invention relates to independent or detached heddles, drop wires, or the like, and more particularly to the construction of said heddles so that they may be assembled in an organized series capable of ready selection and separation either by hand or by mechanical devices.

20 This application is a division of my prior, copending application Serial No. 474,885, filed May 8, 1909.

The invention will be best understood by reference to the following description when taken in connection with the accompanying illustration of one specific embodiment thereof, while its scope will be more particularly pointed out in the appended claims.

25 In the drawings: Figure 1 shows an assemblage of detached heddles or drop wires constructed and arranged in accordance with one form of the invention and shown in co-operative relation to mechanical separating or releasing devices; Fig. 2 is an elevation of a metallic heddle or drop wire with the associated devices shown in cross section; and Figs. 3, 4 and 5 are diagrammatic views illustrating the internal variation in form of successive heddles and the relation there-
30 to of the separating or releasing devices at different stages of their operation.

Referring to the drawings, I have shown the invention embodied in the form of detached heddles of the kind usually formed of thin, resilient sheet metal and employed in the loom as drop heddles, but the invention contemplates independent, detached heddles of other forms of construction and also similar loom elements, such as drop bars or drop wires, the term "heddle" being used as a generic term to include those devices as well.

In the specific form of the invention illustrated it will be seen that the heddles or

drop wires are of two different types,—1 and 2. Each heddle is formed with a threading aperture 3 and an elongated slot at the end, the latter serving as a suspension opening and adapted to receive the suspension or hanger bar 4. The slots of the heddles 1 are indicated at 5 and the slots of the heddles 2 at 6.

The upper ends of the slots as well as the apertures 3 coincide in both sets or types of heddles, but the lower ends of the slots 5 are nearer the apertures 3 in the heddles 1 than are the lower ends of the slots 6 in the heddles 2, thereby providing longer slots in the heddles 1 than in the heddles 2. The heddles 2 are furthermore provided with 70 the apertures 7 which are arranged between the apertures 3 and the slots 6 and which coincide in part with the lower ends of the slots 5 in the heddles 1. It therefore follows that when a number of the heddles of both 75 sets are arranged in alinement, a substantially continuous aperture through the series is formed by the apertures 7 and the lower ends of the slots 5 as is shown in Fig. 2.

The internal variation in construction just 80 described however, provides for arranging the heddles in series in alternating order, that is to say, first a heddle of one type and then a heddle of the other type, and so on, so that due to this regular, alternate variation of internal form between successive heddles a holding portion is presented by each heddle which is uncovered by the preceding heddle. By this means separating or releasing devices may be employed so that, 90 when engaging the holding portion of the foremost heddle it will hold back all succeeding heddles of the series, but by being shifted to the holding portion of the next succeeding heddle the first heddle of the 95 series is thereby released or separated while the remaining members of the series are still held back or retained.

The coöperation between the structure of the described forms of heddles and a typical 100 form of mechanical releasing device may be illustrated by the action of the releasing devices shown in the drawings. The heddles being assembled, as indicated in Figs. 5 and 6, they are initially retained 105 in series by means of a retaining and releasing hook 8 formed at one end of a releasing rod 8^x, the latter extending

through the continuous aperture referred to as formed in the series of heddles. The heddles are supported upon a supporting rod 9 which is one member of a two part telescopic shaft, the supporting rod being adapted to fit loosely within the apertures 3 with which the heddles of both sets are provided, and the rods 8^x and 9 being arranged parallel to the suspension bar 4.

10 The slots 5 and apertures 7 are so located with reference to the apertures 3 that the releasing rod 8^x is permitted a free movement in the continuous aperture thereby provided. By reason of the arrangement 15 and relation of the aperture 7 and the slots 5, however, the releasing hook 8, when extending upwardly, is in a position to engage the holding portion of a heddle 2 directly above the aperture, but, when extending 20 downwardly, is in a position to clear the aperture and engage the holding portion of the next adjacent heddle 1 directly below the slot 5. The result is that when the hook extends upwardly, it retains the foremost 25 heddle 2 together with the series behind the same, while releasing the preceding heddle 1. When turned downwardly, it frees or releases the heddle 2, holding back the succeeding heddles 1 together with the series behind 30 the same. In other words, when the hook, which, by analogy, may be compared to the hour hand of a clock, points to twelve, as shown by Fig. 1, it is adapted to retain a heddle 2, but when it is turned to approximately six o'clock, it releases the heddle 2, retaining the succeeding heddle 1. It is apparent, therefore, that, if the heddles are 35 arranged alternately with regard to their structural variation and the releasing rod 8^x with its hook 8 be extended through the substantially continuous aperture thereby formed, continued rotation of the releasing hook in one and the same direction will effect the release of the heddles one by one 40 at half rotation of the hook, while retaining all the remaining heddles of the series.

45 Any suitable mechanism may be provided for turning the releasing shaft, or the same may be turned by hand, as desired, and any 50 desired means may also be employed for maintaining the heddles compacted against the releasing hook. These and other mechanical features relating to the releasing devices form no material part of the present 55 invention which concerns the arrangement or construction of the heddles themselves.

60 The separation of the successive heddles as described may be utilized for any desired purpose. The heddle after being released, for example, may be conveyed to a position where it is adapted to be acted upon by threading devices. In the illustrated embodiment of the invention, the released heddle is adapted to be fed by gravity or other 65 means along the supporting rod 9 and to be

engaged by the turning and facing screw 10 carried by the other member 11 of the telescopic shaft 9 and thereby faced for the threading operation which may be either automatic or non-automatic. As these devices form no part of the present invention, they need not be further described in detail.

70 It will be observed that in the specific form of the invention shown, the heddles are composed of two distinct sets each member 75 of one set differing in its internal formation from a member of the other set in respect to the apertures 7 and the slots 5 and 6, and that to this different varying formation is due the presentation of a holding portion by 80 one member uncovered by the preceding member. It is to be understood, however, that my invention contemplates the employment of a series of heddles of identical construction but wherein the internal formation 85 is such that by the method of assembling them or arranging them in series, as, for example, by a reversal of the position of successive heddles, a holding portion is presented by each heddle uncovered by an aperture in the preceding heddle.

90 I do not herein claim broadly any alternate variation in arrangement or construction of the heddles whether internal or external, claims to that generic feature being 95 embodied in my copending application Serial No. 824, 249 filed March 12, 1914.

100 While for illustrative purposes I have herein shown and described one specific embodiment of the invention, it is to be understood that the same is not limited to the details of form or arrangement herein shown, but that extensive deviations may be made therefrom without departing from the spirit thereof.

105 Claims—

1. A harness comprising a series of individual heddles having means to support them in series, said heddles having thread receiving openings and being internally and 110 differentially fashioned to receive means to determine the release of said heddles from the series in accordance with such differential fashioning.

2. A harness comprising a series of individual heddles having differentially arranged openings to receive means to determine the release of said heddles from the 115 series.

3. A harness comprising a series of individual heddles having suspension openings, adjoining heddles of said series having differentially arranged openings to receive means controlling the release of the heddles singly and successively from the series.

120 4. A harness comprising a series of detached, independent heddles each composed of thin, flat sheet metal and having each a similar exterior, linear contour, but provided each with a releasing aperture, said 13

- heddles being assembled in series to present each a holding portion uncovered by a releasing aperture of the preceding heddle.
5. As a new article of manufacture, a harness comprising a series of detached, independent heddles, having each an aperture, and means for assembling the heddles in an alternately varying arrangement to present a holding portion of each heddle uncovered by the releasing aperture of the preceding heddle.
10. A plurality of heddles of similar exterior linear contour and having each a releasing opening, the internal formation of succeeding heddles differing to present a holding wall uncovered by the releasing opening of the preceding heddle.
15. As a new article of manufacture, a harness consisting of individual, detached, metallic heddles composed of thin, resilient sheet material of similar external, linear contour, each heddle having its flat face formed to present at some part thereof a holding part and each heddle having a releasing opening, and means for holding said heddles in compacted arrangement whereby a continuous aperture is formed through the compact heddles by the successive releasing openings, but a regular alternate variation in position of the holding parts is presented in successive heddles whereby the holding part of one heddle is uncovered by the releasing opening of the preceding heddle.
20. A series of flat metallic heddles having each a releasing opening, and means for holding the heddles in an alternately varying arrangement, whereby a portion of the flat face of each heddle is uncovered by the releasing opening of the preceding heddle.
25. As a new article of manufacture a series of detached metallic heddles composed of thin, resilient sheet material and arranged in a bank or series with their flat faces in contact, successive heddles of the series presenting an alternately different internal structure and each heddle presenting a holding portion uncovered by reason of the internal structure of the preceding heddle.
30. As a new article of manufacture an organized assemblage of detached, independent metallic heddles composed of thin, resilient sheet material and held in a bank or series with their flat faces in contact, the series of heddles being characterized by perforations having a regular alternate variation of form between successive members of the series, the perforation of one heddle uncovering a holding portion of the next succeeding heddle.
35. An assemblage of individual metallic heddles composed each of thin, resilient sheet material, and means for holding the assemblage with their flat faces in contact

to present differentially arranged openings in successive members, the openings in one member uncovering a holding portion of the next succeeding member.

12. As a new article of manufacture a harness composed of a plurality of detached metallic heddles composed each of thin, resilient sheet material, said heddles in series presenting an alternately varying internal arrangement, a portion of each heddle being uncovered by the preceding heddle because of the said alternately varying internal arrangement.

13. The combination with a series of independent metallic heddles each consisting of thin, resilient sheet material, and means for holding the same in regular, alternate internal linear variation as between successive members of the series, the holding portion of each heddle being uncovered by the preceding heddle in virtue of the said alternate, internal, linear variation.

14. As a new article of manufacture, a harness composed of a series of flat, metallic heddles characterized by a regular, alternate, internal, linear variation of the members of the series, said heddles being of generally similar external linear contour whereby they may be held in a compact bank or series, and an internal formation in one uncover a holding portion in the next adjacent one.

15. As a new article of manufacture, a series of independent, flat metallic heddles or the like of similar external linear contour arranged in series to present a compact bank having an alternatingly different internal structure presenting each a holding portion uncovered by an opening in the preceding one.

16. An assemblage of individual, flat metallic heddles having differentially arranged openings in successive members of the series, said heddles being of generally similar external linear contour whereby they may be held in a compact bank and a holding portion of one uncovered by an opening in the preceding one.

17. A harness composed of a series of flat metallic heddles having differentially arranged openings to receive means to determine the release of said heddles from the series, said heddles being arranged with their flat faces in contact and in a bunched series whereby an opening in one heddle uncovers a holding portion of the next succeeding heddle.

18. A harness comprising a series of flat, metallic heddles of generally similar external linear contour but having differentially arranged openings to receive means to determine the release of said heddles from the series.

19. A harness comprising a series of flat, metallic heddles arranged in series to pre-

sent an alternately different structure, each heddle having a holding portion exposed by the structure of the preceding heddle, but the heddles being arranged in substantial alinement whereby they are presented in a compact bank or series.

20. A harness comprising a series of flat, metallic heddles each composed of thin, resilient material having each a cut-a-way portion, the heddles being arranged with the edges in substantial alinement to present a compact bank but the cut-a-way portions being arranged in regular, alternate variation whereby the holding portion of each heddle is exposed by the cut-a-way portion of the succeeding heddle.

21. The combination of a plurality of heddles or similar loom elements having releasing openings differently arranged in successive handles, a releasing opening in one uncovering a holding portion in another.

22. As a new article of manufacture, a heddle composed of a thin metal plate and having an opening for suspending the same, a thread-receiving opening, and also a selecting formation situated intermediate its ends whereby it is adapted when arranged in series with others to uncover a holding portion on the next adjacent heddle.

23. As a new article of manufacture, a harness consisting of individual, detached, metallic heddles or the like, each composed of flat strips of thin, resilient sheet material presenting flat faces whereby the said heddles may be held with substantially their

entire flat faces in working contact and in a closely compacted and unseparated bank, said heddles having an alternately different internal formation, and means for holding said heddles in the form of an organized harness with the major part of the body portion of successive heddles in substantial registration and alinement and presenting each a holding portion uncovered by the internal formation of the preceding heddle.

24. As a new article of manufacture, a harness consisting of individual, detached, metallic heddles or the like, each composed of flat strips of thin, resilient sheet material presenting flat faces whereby the said heddles may be held with substantially their entire flat faces in working contact and in a closely compacted and unseparated bank, said heddles having releasing openings and means for holding the said heddles in the form of an organized harness with the major part of the body portion of successive heddles in substantial registration and alinement and with the releasing openings in regular, alternate variation for successive heddles of the harness, each opening uncovering a portion of the flat face of the succeeding heddle.

In testimony whereof, I have signed my name to this specification, in the presence of two subscribing witnesses.
